(57) **CLAIM**

The ornamental design for a suitcase, as shown and described.

DESCRIPTION

FIG. 1 is a front, left perspective view of a suitcase showing my new design.

FIG. 2 is a front elevational view thereof.

FIG. 3 is a rear elevational view thereof.

FIG. 4 is a left side elevational view thereof.

FIG. 5 is a right side elevation view thereof.

FIG. 6 is a top plan view thereof.

FIG. 7 is a bottom plan view thereof.

FIG. 8 is a front elevational view thereof in a fully extended state.

FIG. 9 is a left side elevational view thereof in a fully extended state.

FIG. 10 is a right side elevational view thereof in a fully extended state.

FIG. 11 is a top plan view thereof on a reduced scale showing a state in which a handle part is extended; and, FIG. 12 is a top plan view thereof on a reduced scale showing a state in which the suitcase is opened and three flap parts are unfolded.

The broken line showing of portions of the suitcase form no part of the claimed design.

1 Claim, 12 Drawing Sheets
